DUAL SOCKET, BOLT-HOLDING TYPE WRENCH

Alfred H. Lehmann, Park Ridge, Ill.

Application August 30, 1955, Serial No. 531,409

3 Claims. (Cl. 81—55)

This invention relates to combination tools and more particularly to a combination tool for assembling and disassembling a plurality of rotatably engaged work pieces.

The invention is primarily directed to a combination tool for use in servicing oil burner nozzle assemblies which comprise a nozzle body having a tool engaging surface, a nozzle having a similar tool engaging surface and a core threadedly received within the nozzle and having a slot for engagement by a bladed tool such as a screw driver.

Prior to the present invention there was no satisfactory tool for quickly and safely disassembling the constituent elements of an oil burner nozzle assembly without damage to the fuel lines or injury to the service man. Since the nozzle body is connected directly to the fuel line it was possible to restrain rotation of this element with an open end wrench while the nozzle itself was removed by a socket wrench. However, the procedure involved several obvious disadvantages. Conventional open end wrenches tend to slip, particularly when the nozzle body was coated with oil and, furthermore, the limited grip effected by such wrenches caused burring of the edges of the cooperating surfaces of the parts. In addition, the pressures exerted by separate wrenches held in the customary manner was likely to be uneven resulting in possible distortion and rupture of the fuel line. Subsequent removal of the core from the nozzle presented a further difficulty because, in using a conventional screw driver, the nozzle had to be held by the service man with a separate wrench, which was an awkward operation and likely to lead to serious injury if the screw driver were to slip. Moreover, removal of the nozzle from the wrench was often difficult because of the presence of accumulated foreign matter.

With the foregoing in mind a principal object of the invention is to provide a combination tool by means of which an oil burner nozzle assembly may be expeditiously and safely assembled or disassembled.

Another object of the invention is to provide a tool of the stated type in which the nozzle body and nozzle of an oil burner may be securely grasped and rotated with respect to one another, in which integral means are provided for engaging the slot of the core and rotating it with respect to the nozzle, and in which means are provided for ejecting the nozzle from the tool.

A further object of the invention is to provide a device of the mentioned character wherein work pieces of varying lengths may be effectively assembled and disassembled as required.

Other and further objects, advantages and features of the present invention will be apparent to those skilled in the art from the following description, taken in conjunction with the accompanying drawing in which:

Fig. 1 is an elevational view, partly in section, of a combination tool made in accordance with the present invention;

Fig. 2 is a side elevational view of a nozzle assembly with which the tool of the present invention is used;

2

Fig. 3 is an elevational view of the nozzle body of the nozzle assembly of Fig. 2;

Fig. 4 is a vertical sectional view of the nozzle of Fig. 2 showing the core in operative position;

5 Fig. 5 is an elevational view, in section, of the core engaging means of the present invention shown in the position it assumes when the nozzle is ejected;

Fig. 6 is an end view, in section, taken substantially on the line 6—6 of Fig. 1;

10 Fig. 7 is an end view, in section, taken substantially on the line 7—7 of Fig. 1; and

Fig. 8 is an end sectional view taken substantially on line 8—8 of Fig. 1.

With reference to the drawing and more particularly to Fig. 1 the combination tool of the present invention includes a first sleeve 10 having a socket 11 opening into one end for engaging a nozzle body A for which purpose the internal surface of the socket is provided with twelve splines 20 of well-known form for engaging the hexagonal nut faces of the part (Fig. 6). A cylindrical bore 12 opens into the other end of the sleeve 10 and terminates at an internal bead 13 which separates the same from the socket 11. Adjacent the end into which the bore 12 opens there is provided a radially positioned circular aperture 14. A collar 15 is mounted at the upper end of the sleeve 10 and is provided with a flange 16 which normally abuts the edge 17 of the sleeve 10. The bore 20 defined by the flange 16 is at least as large as the bore 12. A threaded aperture 18 coaxial with the bore 14 is formed 20 in the collar 15 for reception of an elongated handle 19 which is provided with a pilot 22 extending through the aperture 14 and protruding into the bore 12 for a purpose hereinafter described.

According to the present invention means are provided for simultaneously grasping a pair of work pieces so that assembly and disassembly thereof may readily be effected. In the present instance, a second sleeve 23 is slidably and rotatably received in the bore 12, and is provided at one end thereof with a socket 24 for grasping 30 a nozzle B and for which purpose it is provided with splines 21 (Fig. 7) for grasping the tool engaging surfaces of the nozzle B. Opening into the opposite end of the second sleeve 23 is a bore 25 which forms, in conjunction with the socket 24, a shoulder 26. Bore 25 receives 35 an enlargement forming the end of an L-shaped handle 28, the shorter leg 29 of which is held with respect to the sleeve 23 by a set screw 32.

According to another important aspect of the present invention sleeve 23 is slideable axially in the bore 12 to 40 accommodate work pieces of varying lengths. For instance, in the event that it is necessary to service a nozzle assembly in which the nozzle body A is longer than normal and/or which may have tool engaging surfaces offset with respect to the mid-transverse plane so that the longer 45 portion extends into the bore 12, the sleeve 23 may be slid in the bore until it is stopped by the pilot 22. In its excursion in the other direction movement is limited by the bead 13.

The present invention contemplates the provision of 50 integrally mounted means for separating a core C from the nozzle B. Such means is mounted on the free end of the longer leg 36 of the lever arm 28. Referring more particularly to Figs. 1 and 5, the leg 36 is provided with a reduced portion 30 defining a shoulder 37. The extreme end of the leg 36 is formed as a blade 38 for 55 reception in the slot 39 in the core C. A sleeve 42 is slidably supported on the arm 36 and has an internal peripheral flange 43 to receive the portion 30. A third sleeve 45 is secured to the sleeve 42 by a stud 46 which is threaded at 47 for reception in a correspondingly threaded aperture 48 in the sleeve 45. The inner end of the stud 46 is received in a countersink 49 in the sleeve 60

42 so that relative rotation between these members is prevented. The outer end of the stud 46 is knurled at 52 for easy grasping for rotation of the sleeve 45 relative to the portion 36 with the result that the core C may be removed from the nozzle B, while the latter is restrained in the suitably splined socket 53 opening into the outer end of the sleeve 45. The parts 42 and 45 are maintained in the normal position shown in Fig. 1 by means of a compression spring 54 which urges the parts against a retainer 55, e. g., a split washer.

In using the combination tool of the present invention for disassembling an oil burner nozzle unit (Fig. 2), the sleeve 10 is first slipped over the nozzle body A until the tool engaging surfaces are gripped by the splines 21. Then the cylinder 23 is manipulated by the handle 28 until the nozzle B is received in the socket 24. The handle 19 is then firmly held by the operator while the handle 28 is rotated in a counterclockwise direction, as viewed from the top in Fig. 1. The parts A and B are thus separated and the tool with its therein held part B may be moved away from the part A. Part B may then be extracted and placed in the sleeve 45, where it is adjusted so that the blade 38 is received in the slot 39. The operator then grasps the stud 46 and rotates the cylinder 45 in a counterclockwise direction as viewed from the right in Fig. 1. This rotation disengages the core C from the nozzle B, and the nozzle B is consequently urged to the right. When separation of these elements has been completed, the core and nozzle are ejected from the cylinder 45 when the operator moves the parts 42 and 45 to the left and compresses the spring 54.

While I have shown a particular embodiment of my invention, it will be understood, of course, that I do not wish to be limited thereto since many modifications may be made and I therefore contemplate by the appended claims to cover any such modifications as fall within the true spirit and scope of my invention.

I claim:

1. A combination tool for separating rotatably engaged work pieces comprising a first sleeve having a splined socket for engaging one of the work pieces interiorly of one end thereof, an elongated bore opening into the other end of said sleeve and communicating with said socket, a bead interiorly of the sleeve separating said socket and bore, a second sleeve slidably received in said bore for rotational and axial movement with respect to said bore within predetermined limits, said second sleeve having a splined socket opening into one end thereof and communicating with the socket of said first sleeve, a collar mounted on said first sleeve in adjacent relation to said other end thereof to provide a peripheral enlargement thereof and having an internal flange abutting said other end, said flange defining an opening at least as large in diameter as said bore, said first sleeve and collar having a radially-directed common aperture communicating with said bore, an elongated handle secured in said common aperture and projecting into said bore to limit movement of

said second sleeve, and an L-shaped lever arm having one leg secured in said second sleeve for relative rotation of said sleeves.

2. A combination tool for separating rotatably engaged work pieces comprising a first sleeve having splines for engaging one of the work pieces interiorly of one end thereof, an elongated bore opening into the other end of said sleeve and communicating with said socket, a second sleeve slidably mounted in said bore for rotational and axial movement with respect thereto, said second sleeve having a socket opening into one end thereof for engaging the other of the work pieces and communicating with the socket of said first sleeve, said first sleeve having a radial aperture adjacent said other end thereof, a collar mounted on said first sleeve adjacent said other end thereof, said collar and first sleeve having a common radially-directed opening, an elongated handle received in said opening and protruding into said bore to limit axial movement of said second sleeve, an L-shaped handle having one leg secured to said second sleeve for rotation thereof and the other leg extending in substantial parallelism with said first handle.

3. A combination tool for separating a pair of threadedly engaged work pieces each having a polygonal portion for engagement by a tool comprising a first sleeve having a socket conforming to the tool-engaging portion of one work piece at one end of the sleeve and a coaxial smooth bore at the other end thereof, said socket and bore being in communication, a projection interiorly of said sleeve and between said socket and bore, a second sleeve having a socket conforming to the tool-engaging portion of the other work piece, said second sleeve being slidably received in said bore for rotational and axial movement relatively thereto, a first handle for said first sleeve including a threaded part at one end, said first sleeve having a threaded aperture for reception of said threaded part and the relative dimensions of said first sleeve and threaded part being such as to cause a portion of said end of said handle to protrude into the interior of the sleeve to prevent dislodgment of said second sleeve from said bore and said handle, when unscrewed, permitting separation of said sleeves, and a handle for said second sleeve.
